COMBINED RUFFLING AND PINKING DEVICE
FOR SEWING MACHINESJoseph Cosentino, Richmond Hill, N. Y., assignor
to Man-Sew Pinking Attachment Corp., New
York, N. Y., a corporation of New York

Application August 3, 1940, Serial No. 350,656

7 Claims. (Cl. 112—124)

This invention relates to a combined ruffling and pinking device for sewing machines and has for its general object and purpose to provide a simple and efficiently operating mechanism especially designed for application and use in connection with modern high speed factory production sewing machines, whereby garment materials may be simultaneously ruffled and edge pinked and the two pieces of fabric accurately stitched together to form an ornamental seam.

It is a more particular object of the invention to provide in combination with a pinking device of the type disclosed in Patent No. 2,142,682 issued to Man-Sew Pinking Attachment Corp., January 3, 1939, a novel form and construction of combined ruffling and feeding blade which operates to produce accurately formed ruffles in one piece of fabric and to feed the edge of said fabric piece and the superposed edge of a second fabric piece to the pressure roller of the pinking device so that in the operation of said device lateral pull or strain on the fabric pieces adjacent to the stitch forming needle will be prevented and a straight undeviating line of stitching connecting the fabric pieces with each other will be produced.

It is another important object of the invention to provide a combined ruffling and pinking means which will enable the line of stitching to be located very close to the fold formed in the edge of one piece of fabric and in accurate parallel relation therewith.

It is a further detail object of the invention to provide a simply constructed one-piece blade having independently acting parts, one of which forms the ruffles in one piece of fabric and feeds the same to the sewing machine needle while the other part of said blade has resilient pressure engagement upon the superposed edges of the two pieces of fabric and feeds the same after they have been stitched together to the rotating cutter of the pinking device.

With the above and other objects in view, the invention consists in a combined ruffling and pinking device for sewing machines, and in the form, construction and relative arrangement of its several parts, as will be hereinafter more fully described, illustrated in the accompanying drawing and subsequently incorporated in the subjoined claims.

In the drawing wherein I have shown one simple and practical embodiment of the invention and in which similar reference characters designate corresponding parts throughout the several views:

Fig. 1 is a top plan view of the ruffling and pinking device, showing the combined ruffling and feeding blade in its retracted position.

Fig. 2 is a side elevation thereof.

Fig. 3 is a fragmentary inner face view of the fabric seam, and

Fig. 4 is a similar fragmentary view of the outer or exposed face of the fabric seam.

Referring in detail to the drawing, in Fig. 1 thereof I have shown a section of the bed plate 5 of the sewing machine upon which the base 6 of the pinking device is suitably secured. This device includes the pinking ring or cutter 7 mounted upon base 6 to rotate in a horizontal plane and the pressure roller 8 which presses the edges of the fabric pieces upon the pinking teeth of the cutter 7. Further detail description of this pinking device is unnecessary for the purpose of the present application, as reference may be had to the issued patent above referred to.

The diametrical axis of the cutter 7 and of the roller 8 at right angles to the line of feed of the fabric materials, is located rearwardly of the plane of the vertically vibrating needle 9 and the teeth of the cutter beneath the roller 8 approach very closely to the seam line formed by said needle so that a garment seam may be formed having relatively narrow pinked edges projecting from one side of the line of stitching.

In conjunction with the needle 9, the usual presser foot 10 is employed with which the conventional feed dog mechanism, such as that shown in said issued patent, cooperates to intermittently feed the fabric materials to the stitch forming mechanism of the machine.

In combination with the pinking means above referred to, I prefer to employ a type of ruffling mechanism, in which the individual ruffles are formed in one piece of fabric and positioned for stitching to a second piece of fabric in the up-stroke of the needle 9. In the drawing I have illustrated a part of such a ruffling mechanism which is similar to that shown and described in the pending application for patent of Victor J. Sigoda filed December 23, 1939, Ser. No. 310,844. The housing 11 for the actuating mechanism of the ruffling blade is attached to the end face of the sewing machine arm (not shown) and said mechanism operatively connected with the needle actuating shaft of the sewing machine. On the lower end of this housing, the depending oscillating arm 12 is mounted and to the lower end of said arm, one end of the combined ruffling and feeding blade 13 is pivotally connected and normally yieldingly urged downwardly from said arm.

towards the bed plate 5. This blade extends rearwardly towards the needle 9 and is slotted or bifurcated as at 14 to provide an end portion 15 in line with the needle 9 having the toothed or serrated edge 16 disposed at right angles to the line of feed of the material. This toothed edge of the part 15 is yieldingly pressed downwardly upon the surface of a supporting plate 17, over which the lower layer of fabric is fed beneath the inclined guiding bar 18 integrally connected with the base 17 at one edge thereof. The base 17 at its rear edge terminates closely adjacent to the needle 9 and is also toothed or serrated as shown at 19.

At the opposite side of the bifurcation 14, the blade 13 is formed with the part 20 projecting rearwardly beyond the part 15 and angularly offset above the plane thereof for independent resilient yielding movement relative to said part 15. The rear edge of the part 20 is also toothed or serrated as at 21 and cooperates with the toothed edge 23 of a rearward extension 22 of the base plate 17. These two toothed edges 21 and 23 are located above and extend across the teeth of the rotatable pinking member 7 in advance of the pressure roller 8.

Above the ruffling blade 13, there is arranged a longitudinally inclined folder guide 24 for the second fabric layer. This second fabric layer extends through said guide 24 and above the parts 15 and 20 of the reciprocating blade 13. After the bight of said fold passes rearwardly of the needle 9, said second fabric layer extends upwardly over the pressure roller 8 of the pinking device in the manner shown in said issued patent. In Figs. 3 and 4 of the drawing, I have shown the lower fabric layer which moves over the supporting base 17, at 25 and the upper fabric layer which moves through the folder guide 24, at 26. 27 indicates the folded edge portion of the latter fabric layer which extends through slot 14 beneath the part 20 and is superimposed upon the edge portion 28 of the fabric layer 25. Thus it will be understood that only these superimposed edge portions of the two pieces of fabric, after passing beyond the toothed edge 21 of the blade 13, are pressed upon the teeth of the cutting member 7 by the roller 8 while the body of the fabric layer 26 extends upwardly around and above said pressure roller.

If desired, as shown in Fig. 4 of the drawing, a narrow ornamental braid strip 29 may be fed under the supporting base 17 with the fabric layer 25 in line with the needle 9 to be stitched to the two pieces of fabric in overlying relation with the ruffles formed in the fabric layer 25.

In the operation of the invention as above described, in the action of the feed mechanism of the sewing machine, the two layers of fabric are progressively fed over the supporting plate 17 and through the folder guide 24 to the needle 9, and as the needle moves upwardly, the ruffer actuating mechanism oscillates arm 12 and moves the blade 13 rearwardly. The toothed edge portion 16 of this blade cooperating with the plate 17 forms a ruffle in the lower fabric layer 25 and projects the same beyond the toothed edge 19 of said plate, under the presser foot and in position for penetration by the thread carrying needle 9 of the stitching mechanism. The upper fabric layer 26 in its movement through the guide 24 has its edge portion infolded as at 27 and disposed in superimposed relation upon the ruffled edge of the fabric layer 25 as it is drawn beneath the presser foot. Concurrently with this

ruffle forming action of the part 15 of blade 13, the toothed edge 21 of the part 20 of said blade, resiliently bearing upon the upper side of the fold 27, projects said folded edge of the fabric layer 26 which has been previously stitched to the underlying ruffled edge of the fabric layer 25 beyond the teeth 23 of the stationary plate 22 and feeds the same beneath pressure roller 8 to the teeth of the pinking member 7. The teeth 21 being engaged with the fold 27 at a point rearwardly of the needle 9 prevents lateral pull of the fabric layer 25 in the arcuate movement of the teeth of the pinking member 7 so that in the downstroke of the needle 9 and as the blade 13 is retracted, a continuous straight line of stitching indicated at 30 will be formed, securely uniting the pinned edges of the two layers of fabric, in close parallel relation to the bight of the fold 27 in the fabric layer 26. In the retraction of the blade 13 as the needle moves downwardly, the two fabric layers are held against movement therewith by the toothed edges 19 and 23 of the stationary plate 22. In this manner, ruffles of substantially uniform width are formed in the edge of the lower fabric layer 25 and said ruffled edge and the infolded edge 27 of the fabric layer 26 are positively fed to the cutting teeth of the pinking member 7 by independent though concurrent operation of the part 20 of said blade which also acts to prevent lateral movement or displacement of the superimposed edges at the point of penetration by the stitch forming needle 9. This results in an accurately registered relation of the pinking cuts in the edges of the two layers of fabric and also a line of stitching spaced a minimum distance from the seam fold and in undeviating parallel relation with the fold line of the fabric layer 26.

From the foregoing description considered in connection with the accompanying drawing, the construction and manner of operation of the present invention will be clearly understood. I have disclosed an application thereof in connection with the making of a particular type of dress or garment seam, though it will be understood that the invention may likewise be employed for simultaneously ruffling and pinking the edge of a single layer of fabric, or in the manufacture of other types of garment seams. In practical tests of the invention, it has been found very satisfactory for the large quantity production of such ornamented garment materials upon modern high speed sewing machines. Both the pinking and ruffling devices are of comparatively simple mechanical construction and readily adaptable to various standard makes of sewing machines for efficient and reliable operation in connection therewith and without requiring mechanical alterations in such machines of a material character.

While I have herein shown one practical and preferred embodiment of the present improvements, it is nevertheless to be understood that the essential features thereof are susceptible of embodiment in various other alternative mechanical forms. Accordingly, I reserve the privilege of resorting to all such legitimate changes or modifications in the form, construction and relative arrangement of the several cooperating elements as may fairly be comprehended within the spirit and scope of the appended claims.

I claim:

1. In combination with a sewing machine having standard feed mechanism and a vertically reciprocating needle; a rotatable trimming mem-

ber having cutting engagement with the material rearwardly of the needle and adjacent the line of stitching formed thereby, a ruffling device including an oscillatory ruffling blade mounted in advance of the needle, and means engaging the material between the needle and the point of contact of the trimming member with the material to resist pulling strain on the material at the point of stitching in an angular direction with respect to the path of movement of the material.

2. In combination with a sewing machine having standard feed mechanism and a vertically reciprocating needle; a rotatable trimming member having cutting engagement with the material rearwardly of the needle and adjacent the line of stitching formed thereby, a ruffling device including an oscillatory ruffling blade mounted in advance of the needle, and means concurrently operable with the ruffle forming movement of said blade to simultaneously and positively feed a previously ruffled and stitched section of the material to said trimming member.

3. In combination with a sewing machine having standard feed mechanism and a vertically reciprocating needle; a rotatable trimming member having cutting engagement with the material rearwardly of the needle and adjacent the line of stitching formed thereby, a ruffling device including an oscillatory ruffling blade mounted in advance of the needle, said blade having a ruffle forming part engaging the material in line with the needle and also having a second resiliently yieldable part exerting pressure upon the material at one side of the needle and rearwardly thereof to positively feed the material to said trimming member and resist pulling strain upon the ruffled material at the point of stitching in an angular direction relative to the path of movement of the material.

4. In combination with a sewing machine having standard feed mechanism and a vertically reciprocating needle; a rotatable trimming member having cutting engagement with the material rearwardly of the needle and adjacent the line of stitching formed thereby, a ruffling device including an oscillatory ruffling blade mounted in advance of the needle, said blade having a ruffle forming part engaging the material in line with the needle and also having a second resiliently yieldable part exerting pressure upon the material at one side of the needle and rearwardly thereof to positively feed the material to said trimming member and resist pulling strain upon the ruffled material at the point of stitching in an angular direction relative to the path of

movement of the material, and a stationary means associated with each of said parts of the ruffling blade to engage and hold the ruffled material relative to the needle and trimming member respectively in the retracting movement of said blade.

5. In combination with a sewing machine having standard feed mechanism and a vertically reciprocating needle; a pinking member mounted to rotate in a horizontal plane and having cutting engagement with the material rearwardly of the needle and adjacent the line of stitching formed thereby, pressure applying means associated with said pinking member, a ruffling device including an oscillatory ruffling blade mounted in advance of the needle, and said blade having independently acting parts adapted respectively to form ruffles in the material and position the same relative to said needle, and to positively feed previously ruffled and stitched sections of the material to said pressure applying means.

6. In combination with a sewing machine having standard feed mechanism and a vertically reciprocating needle; a pinking member mounted to rotate in a horizontal plane having cutting engagement with the material rearwardly of the needle and adjacent the line of stitching formed thereby, pressure applying means associated with said pinking member, means for guiding two layers of fabric to the needle and for forming a fold in the edge of one fabric layer and positioning the same in superposed relation upon the edge of the other fabric layer, and a ruffling device including an oscillatory blade having independently acting parts one of which forms ruffles in the latter fabric layer and positions the same relative to the needle, the other part of said blade resiliently bearing upon the superimposed edges of the fabric layers to positively feed the same to said pressure applying means.

7. In a ruffling device adapted for cooperation with stitching and trimming mechanism of a sewing machine, an oscillatory blade having a longitudinally bifurcated end portion providing spaced relatively yieldable parts of relatively different lengths, one of said parts adapted to form ruffles in the fabric material and position the same relative to the stitching mechanism, and the other part of said blade extending beyond said first named part and adapted for engagement with ruffled and stitched sections of the material to positively feed the same to the trimming mechanism in each ruffle forming movement of said blade.

JOSEPH COSENTINO.
